EQUALIZING MECHANISM

Ernst F. Muller, Columbus, Ohio, assignor to The Jeffrey Manufacturing Company, Columbus, Ohio, a corporation of Ohio

Application January 14, 1931, Serial No. 508,751

19 Claims. (Cl. 262—28)

The present invention relates to equalizing mechanism for maintaining the parallelism of two parallel members of which one is movable toward and away from the other.

5 While the invention is of general application, I shall describe it in connection with a mining machine wherein means are provided for moving an elongated cutter bar toward and away from a supporting element to position the 10 bar in the desired working planes. Assuming the cutter bar to be positioned for cutting in a horizontal plane, the equalizing mechanism to be described assures the maintenance of the cutter bar against angular deviation from such 15 plane and assures translational movement of the cutter bar when the latter is being adjusted to another plane.

The application of the invention to a mining machine has given rise to certain novel changes 20 in mining machine structure which also form a part of the present invention.

An illustrative embodiment of the invention is shown in the accompanying drawings in which

25 Figure 1 is a top plan view of a machine embodying the invention;

Figure 2 is a side elevation of the machine of Figure 1;

Figure 3 is a section on line 3—3 of Figure 1;

30 Figure 4 is a section on line 4—4 of Figure 3; and

Figure 5 is a section on line 5—5 of Figure 3.

Referring to the drawings, reference numeral 10 designates generally a wheel mounted truck adapted to be propelled over a mine track by means of a motor 11. Mounted at the forward 35 end of the truck on vertically adjustable pedestals 12, 13 and 14 is a ring 15 carrying rollers 16 projecting somewhat above the top edge of the ring to rotatably support a turn-table 17. Mounted in a recess in the top of the turn-table is a reversible motor 18 here shown as an electric 40 motor.

Mounted in a vertical bearing sleeve 19 intersecting the axis of the armature shaft 20 of the motor, is a shaft 21 provided with a thrust flange 22 bearing on a thrust bearing 23 in a recess 24 at the top of the bearing sleeve.

A bevel gear 25 keyed to shaft 21 below sleeve 45 19 is engaged by armature pinion 26 for driving shaft 21. Fixed on the hub of gear 25 is an eccentric 27 engaged by strap 28 which through suitable pawl and ratchet mechanism (not shown) is adapted to drive the clutch controlled drum 29 mounted on the turn-table. A draft device 30 is adapted to be reaved in either direc-

tion about sheaves mounted on the platform and its free end anchored as at 31, whereby tensioning of the draft device through rotation of the drum is effective to swing the turn-table in the desired direction. This turn-table swinging mechanism is well known in the art and consequently does not require particular description here. As is further customary, the edge of the turn-table is provided with notches as at 31' adapted to be engaged by a locking lug to maintain the turn-table in the desired position of angular adjustment.

Revolved on the upper end of shaft 21 is a sprocket wheel 32 having a hub provided with peripheral teeth 33, similar teeth 34 being provided on an expanded portion of shaft 21 above teeth 33. A ring 35 has internal teeth adapted to engage teeth 33 and 34 when the latter are in register so that rotation of shaft 21 will be imparted to sprocket wheel 32. A screw 36 threaded in an axial bore in the upper end of shaft 21 revolvably supports disc 37 to the lower margins of which ring 35 is fastened. A hand wheel 38 is fixed to the upper extremity of screw 36 and it will be evident that upon rotation of the hand wheel relative to shaft 21 ring 35 will be axially displaced relative to the shaft. When the ring is lifted sufficiently to disengage its teeth from teeth 33 it will be evident that sprocket wheel 32 will be declutched from shaft 21.

Projecting from the turn-table in radial relation to sleeve 19 is an arm 39 which is designed to support the cutter bar and its driving and adjusting mechanism. A frame or head generally designated at 40, Figure 1, has an arm 41 overlying arm 39 and provided with slots 42 through which bolts 42' are passed into threaded bores of arm 39 to secure the two arms together. Due to the elongation of slots 42, the two arms may be longitudinally adjusted upon loosening the bolts so as to alter the distance between sprocket wheel 32 and the head 40, the two arms thus constituting in effect a single telescoping arm. Mounted in a non-rotatable nut 43 in a vertical web portion of the head 40 is a cap screw 44 whose head is adapted to abut the end of arm 39 to hold the head in adjusted position. Upon loosening the connections between arms 39 and 41 and rotating screw 44 to move it outwardly of nut 43 movement of the head away from sprocket wheel 32 will be enforced.

Mounted in a ball bearing assembly 45 which is supported on a vertical axis in a seat 46 provided in the head is a shaft 47. At its upper end, 110

shaft 47 is provided with a spur gear 48 having a sprocket wheel 49 formed therewith, sprocket wheel 49 lying in the same horizontal plane as sprocket wheel 32 and being connected 5 to the latter by means of a chain 50.

To the rear of shaft 47, head 40 is provided with a pair of parallel downwardly extending guide arms 51 and 52 provided with opposed grooves adapted to receive and guide lugs 53 and 10 54 formed on a cutter bar supporting frame 55. At its end opposite lugs 53 and 54, frame 55 is provided with a vertical bore in which is mounted a screw 56, the screw having a polygonal head 57 at its lower end engaged in a mating 15 recess in the frame whereby rotation of the screw relative to frame 55 is prevented. Immediately above the frame, screw 56 is provided with a retaining nut 58. The upper end of screw 56 is engaged in the threaded end of an elongated 20 nut 59 which is journaled in a sleeve bearing 60 provided in a web 61 of head 40. The upper end of nut 59 is guided by an internally projecting boss 62 formed in the cover plate 63 of the head. A spur gear 64 engaging gear 48 is freely 25 revoluble on the upper cylindrical portion of nut 59, the gear having integral therewith, as here shown, a conical clutch element 65 for co-operation with a mating clutch element 66 splined on an intermediate portion of nut 59. 30 The hub of gear 64 rests on a thrust ring 59' fixed on nut 59 against downward displacement. Nut 59 is provided with a thrust flange 67 which bears on the ball bearing assembly 68 to prevent downward displacement of the nut. 35 The hub of clutch element 66 is provided with a peripheral groove 69 in which is mounted a ring 70 carrying trunnion pins 71 and 72, Figure 5. The trunnion pins are engaged in apertures in the twin arms 73 and 74 of a shifting lever 75, lever 75 being pivotally mounted and connected with the head at one end by means of a pin 76 and being provided at its opposite end with a longitudinally extending slot 77. A cylindrical member 78 journaled in the side wall 79 of the 40 head 40 is provided internally of the head with an eccentric pin 80 engaging in slot 77 and externally of the head with an operating lever 45 81.

From the above, it will be evident that gear 64 being rotated, nut 59 may be rotated relative to screw 56 through operation of handle 81 to engage clutch elements 65 and 66, screw 56 in its consequent longitudinal displacement carrying with it frame 55. It will be recalled that motor 18 is reversible so that nut 59 may be driven in either direction to raise or lower frame 55.

At an intermediate portion, frame 55 is provided with a bearing ring 82 in which is journaled a block 83 in coaxial relation with shaft 47, the block having a radially extending foot 84 to which the cutter bar 85 is secured. Secured on a circumferentially shouldered portion of block 83 are a pair of semi-circular segments 86 and 87 whose margins overlie ring 82 to afford a thrust bearing for block 83. The block is flanged as at 88 beneath ring 82 to prevent upward displacement.

Block 83 is provided with a vertical bore extending upwardly through a neck portion 83' and providing a bearing for a sleeve 89 radially expanded at its top for thrust support upon the upper edge of neck 83'. Keyed to the lower end of sleeve 89 and secured thereon by means of a cap screw 90 and washer 91 is a cutter chain drive

sprocket 92 engaging the cutter chain 93 to drive it in the usual manner. Shaft 47 is provided with longitudinally extending grooves as at 94 slidably mating with longitudinally extending ribs 95 formed in the internal walls of sleeve 89 at its upper end, Figures 3 and 4. The telescoping shaft and sleeve form a drive connection between gear 48 and sprocket 92 in all positions of vertical adjustment of frame 55.

Block 83 is provided with an arcuate rib 96 engaging in an arcuate guideway 96' formed on the underside of frame 55 between ring 82 and screw 56. As here shown, rib 96 is provided with a projecting flange 97 engaged in a recess 98 of the frame, the lower face of the flange resting on the lower wall of the recess to provide additional support for block 83. In assembling the parts, the rib and flange are swung into the arcuate guideway and recess from a position in which the cutter bar extends somewhat rearwardly relative 95 to frame 55.

Rib 96 is provided with a number of vertical apertures 99 adapted to be engaged by a pin 100 slidably mounted in a boss 101 of frame 55. At its upper end, pin 100 is provided with a circumferential recess 102 which receives a ring 103 having diametrically opposite trunnion pins 104 and 105 engaged by a shifting yoke 106 which is mounted on a rock shaft 107 journaled on frame 55 and projecting to one side thereof. At its free 105 end, shaft 107 has secured thereto a lever 108, a torsion spring 109 being mounted on the shaft and tending to swing the shaft in such direction as to hold pin 100 in its lower position as shown in Figure 3 wherein it is adapted to project into 110 a registering aperture 99. By lifting the pin through manipulation of lever 108, block 83 may be swung and the pin engaged in another aperture to lock the cutter bar in a different position of angular adjustment relative to the head. 115

The position of screw 56 is preferably so chosen relative to the weight of frame 55, block 83, and the cutter bar that when the cutter bar extends in parallel relation to the head as shown in Figure 1, the screw is at substantially the center of 120 gravity of the combined suspended elements. Due to this disposition of parts, there is a minimum binding tendency between the screw and nut, between shaft 47 and sleeve 89, and between lugs 53, 54, and guides 51, 52. To overcome all dis- 125 tortive tendencies, however, I have provided the mechanism which will now be described.

Journaled in the side walls of head 40 adjacent the top thereof are a pair of transversely extending parallel shafts 110 and 111. Shaft 110 has fixed thereon pinions 112 and 113, one at each side of the head, while the shaft 111 has similarly fixed thereon pinions 114 and 115, the four pinions lying at the corners of a parallelogram. Outwardly of pinions 113 and 115, shafts 110 and 111 have fixed thereon sprockets 116 and 117 respectively, the sprockets being connected by means of a chain 118 adapted to be suitably tensioned through an adjustable slide 119 engaging the upper run of the chain.

Frame 55, Figure 4, is provided adjacent lugs 53 and 54 with outwardly extending lug portions 120 and 121 to which are pivoted through coaxial cap screws 122 and 123, a pair of racks 124 and 125 which extend upwardly and engage pinions 112 and 113 respectively, being held in engagement therewith by the clips or brackets 126 and 127, Figure 1.

At its forward end, frame 55 is provided with a yoke shaped rib 128 terminating in knuckles 150

129 and 130 to which are pivoted through bolts 131 and 132, a pair of racks 133 and 134 which extend upwardly into engagement with pinions 114 and 115 respectively. Racks 133 and 134 are maintained in engagement with their associated pinions by means of clips 135 and 136, Figure 1.

Should the cutter bar be adjusted angularly relatively to the longitudinal line of the head, there would ordinarily be a tendency to throw frame 55 out of balance, that is, to tilt it about a longitudinally extending axis. Any such distortive tendency, however, is at once equalized through the racks. For example, a distortive tendency transmitted through pinions 113 and 15 115 is transmitted thereby through shafts 110 and 111 and pinions 112 and 114 to racks 124 and 133 so that the latter racks are influenced to the same extent and in the same direction as the racks on the opposite side of the head. Due 20 to this equalizing force, the distortive tendency is entirely overcome.

Similarly, a distortive tendency exerted about the transverse axis of frame 55 is transmitted from one of the shafts 110 and 111 to the other 25 through the sprocket chain so that the position of frame 55 is not affected.

The same effects are secured upon vertical adjustment of the frame, the racks interacting to enforce purely translational movement of the 30 frame.

By the described mechanism, it will be seen that under no circumstances can there be a binding between the guiding and adjusting means for the frame 55 and the telescoping drive connection for the cutter chain.

Head 40 projects to a very slight degree above turn-table 17 which itself is mounted in a low lying plane. The machine can be run into spaces restricted as to height wherein vertical adjustment of the turn-table would be impossible, and vertical adjustment of the cutter bar can be obtained through adjustment of frame 55, the cutter bar being adapted to be lowered, if desired, to cut at the level of the mine floor in front of 45 the tracks as shown in Figure 2. The position of shafts 110 and 111 and the length of the racks is so chosen that the racks have a considerable extent of vertical movement before their tops project above the top of head 40. It will be seen 50 that I have provided a machine of great adaptability and yet extremely compact so that it may operate in places hereto inaccessible to similar types of machines.

While I have described a specific embodiment 55 of the invention, it will be understood that I do not limit myself to the exact mining machine structure shown nor to the application of the new equalizing mechanism to such a machine. I do not limit myself except as in the following 60 claims.

I claim:

1. The combination with two substantially parallel members of which one is displaceable toward and away from the other, and means operable 65 to effect displacement of the displaceable member, of equalizing means exclusive of said first named means and comprising a pair of parallel shafts journaled in one of said members in parallel relation to the other, a sprocket wheel fixed 70 on each shaft, a chain connecting said sprocket wheels, a pair of spaced pinions fixed on each shaft, the pinions being positioned as at the corners of a parallelogram, and racks pivoted to said other member as at the corners of a parallelogram substantially equal to that above mentioned,

one of said racks being engaged with each of said pinions.

2. In a machine of the class described, a horizontally projecting arm, a cutter bar supporting frame beneath said arm and substantially parallel thereto, means for adjusting said frame toward and away from said arm, and equalizing means exclusive of said adjusting means acting on said frame at a plurality of spaced points to maintain the parallelism of the frame to the arm in all positions of adjustment relative thereto.

3. In a machine of the class described, a horizontally projecting arm, a cutter bar supporting frame beneath said arm and substantially parallel thereto, means for adjusting said frame toward and away from said arm, and means operated in consequence of movement of the frame relative to the arm and acting on said frame at points adjacent its front and rear ends to maintain the parallel relation of the two members.

4. In a machine of the class described, a horizontally projecting arm, a cutter bar supporting frame beneath said arm and substantially parallel thereto, means for adjusting said frame toward and away from said arm, a plurality of means exclusive of said adjusting means interposed between the arm and frame and connected to the latter at spaced points, and a connection between said last named means rendering them mutually reactive to distortive forces applied to the frame whereby to maintain the latter in parallelism with the plane of the arm.

5. In a machine of the class described, a horizontally projecting arm, a cutter bar supporting frame beneath said arm and substantially parallel thereto, means for adjusting said frame toward and away from said arm, equalizing means exclusive of said adjusting means and comprising a plurality of rod-like elements connected at one end to the frame, guide means on the arm for the other ends of said rod-like elements, and a connection including rotary transmission means between said other ends of said rod-like elements, said connection rendering said elements mutually reactive to distortive forces applied to the frame whereby to maintain the latter in parallelism with the arm.

6. In a machine of the class described, a horizontally extending arm, a cutter bar supporting frame beneath said arm and substantially parallel thereto, a pair of parallel horizontal shafts journaled in said arm, a pair of pinions fixed in spaced relation on each of said shafts, substantially vertical racks engaging said pinions, means pivotally connecting the lower ends of said racks to said frame, gearing connecting said shafts, screw and nut suspension means between said arm and frame, and means for relatively adjusting the screw and nut for vertically displacing the frame.

7. In a machine of the class described, a horizontally extending support, a frame beneath said support and parallel thereto, a cutter bar projecting from said frame, suspension means between the support and frame supporting the frame for vertical adjustment relative to the support, guide means comprising rigid means depending from the support and presenting a vertical guideway and means on the frame remote from said suspension unit slidably engaged with said guideway, said guide means serving to hold the frame against rotary movement relative to the support about a vertical axis, and equalizing means exclusive of said suspension means and guide means and acting on said frame at a plurality of spaced points thereon to maintain the

parallelism of the frame to the support in all positions of adjustment relative thereto.

8. In a machine of the class described, a horizontally extending support, a frame beneath said support and parallel thereto, a cutter bar projecting from said frame, screw and nut suspension means between the support and frame and operable to adjust the latter vertically relative to the former, interengaged guide means presented by the support and frame and holding the latter against rotary movement relative to the former about a vertical axis, and equalizing means exclusive of said suspension means and guide means and acting on said frame at a plurality of spaced points thereon to maintain the parallelism of the frame to the support in all positions of adjustment relative thereto.

9. In a machine of the class described, a horizontally extending support, a frame beneath said support and parallel thereto, a cutter bar projecting from said frame, suspension means between the support and frame supporting the frame for vertical adjustment relative to the support, guide means comprising rigid means depending from the support and presenting a vertical guideway and means on the frame remote from said suspension unit slidably engaged with said guideway, said guide means serving to hold the frame against rotary movement relative to the support about a vertical axis, equalizing means exclusive of said suspension means and guide means and acting on said frame at a plurality of spaced points thereon to maintain the parallelism of the frame to the support in all positions of adjustment relative thereto, said equalizing means comprising a pair of parallel horizontal shafts journaled in said support, a pair of pinions fixed in spaced relation on each of said shafts, substantially vertical racks engaging said pinions with their upper ends and having their lower ends in connection with the frame, and gearing connecting said shafts.

10. In a machine of the class described, a horizontally extending support, a frame beneath said support and parallel thereto, a cutter bar projecting from said frame, screw and nut suspension means between the support and frame and operable to adjust the latter vertically relative to the former, interengaged guide means presented by the support and frame and holding the latter against rotary movement relative to the former about a vertical axis, equalizing means exclusive of said suspension means and guide means and acting on said frame at a plurality of spaced points thereon to maintain the parallelism of the frame to the support in all positions of adjustment relative thereto, said equalizing means comprising a pair of parallel horizontal shafts journaled in said support, a pair of pinions fixed in spaced relation on each of said shafts, substantially vertical racks engaging said pinions with their upper ends and having their lower ends in connection with the frame, and gearing connecting said shafts.

11. In a machine of the class described, a horizontally extending support, a frame beneath said support and parallel thereto, a cutter bar projecting from said frame, screw and nut suspension means between the support and frame and operable to adjust the latter vertically relative to the former, guide means comprising rigid means depending from the support and presenting a vertical guideway and means on the frame remote from said suspension unit slidably engaged with said guideway, said guide means

serving to hold the frame against rotary movement relative to the support about a vertical axis, and equalizing means exclusive of said suspension means and guide means and acting on said frame at a plurality of spaced points thereon to maintain the parallelism of the frame to the support in all positions of adjustment relative thereto.

12. In a machine of the class described, a horizontally extending support, a frame beneath said support and parallel thereto, a cutter bar projecting from said frame, screw and nut suspension means between the support and frame and operable to adjust the latter vertically relative to the former, guide means comprising rigid means depending from the support and presenting a vertical guideway and means on the frame remote from said suspension unit slidably engaged with said guideway, said guide means serving to hold the frame against rotary movement relative to the support about a vertical axis, equalizing means exclusive of said suspension means and guide means and acting on said frame at a plurality of spaced points thereon to maintain the parallelism of the frame to the support in all positions of adjustment relative thereto, said equalizing means comprising a pair of parallel horizontal shafts journaled in said support, a pair of pinions fixed in spaced relation on each of said shafts, substantially vertical racks engaging said pinions with their upper ends and having their lower ends in connection with the frame, and gearing connecting said shafts.

13. In a mining machine, the combination with a truck adapted to travel along a mine track, of a supporting frame mounted on said truck to have a relatively low overall height, a motor at the top of the said frame, and power-transmission means between said motor and said kerf-cutter to drive the same and adjust the position thereof relative to said frame, said power transmission means comprising a train of sprocket and spur gearing substantially at the top of the said frame and all operating on vertical axes.

14. In a mining machine, the combination with a supporting frame, of a cutter bar pivoted thereto for angular adjustment, means for locking said cutter bar in adjusted angular position, and an open ended arcuate interlocking connection between said cutter bar and said frame for compelling said cutter bar to move bodily with said frame when the latter is moved at right angles to the plane of said cutter bar.

15. In a mining machine, the combination with a supporting frame, of a cutter bar pivoted thereto, a pin on said frame adapted to extend into any one of a plurality of holes in said cutter bar to hold the latter in adjusted angular position, and an arcuate interlocking tongue and groove connection between said frame and said cutter bar to compel the latter to move bodily with said frame when the latter is moved at right angles to the plane of said cutter bar, said connection having an open end.

16. In a mining machine, the combination with a supporting frame, of a chain-carrying cutter bar, a supplemental frame carrying said cutter bar, and movable relative to said supporting frame in a direction at right angles to the plane of said cutter bar, means on said supporting frame for guiding said supplemental frame in its movement relative to the supporting frame, means for driving the chain on said cutter bar, mechanism for adjusting the position of said cutter bar by moving the same along said sup-

porting frame, and equalizing mechanism between said frames to prevent binding when said frames are moved relatively to each other.

17. In a machine of the class described, a horizontally extending arm, a frame spaced from said arm, a cutter bar projecting from said arm, a telescopic drive shaft for the cutter bar extending between said arm and frame, drive gearing for said shaft extending along said arm and closely confined to the vicinity thereof, means for adjusting said frame toward and away from said arm comprising screw and nut elements extending between said arm and said frame on an axis parallel to the axis of said shaft and spaced from the latter toward the free end of said arm, and drive means for one of said elements including intermeshed gears coaxial with said shaft and said elements respectively, and disposed immediately adjacent said arm, said drive means also including clutch means.

18. In apparatus of the class described, a cutter bar support, mounting means for a cutter bar pivoted to said support, said support having an arcuate ledge thereon concentric with the pivoting axis of said mounting means, said ledge having a face in a plane at right angles to said pivoting axis, and radially projecting means on said mounting means engaging said face for the support of said mounting means, said projecting

means being movable in contact with said face during swinging movement of said mounting means relative to said support throughout a certain range and being disengageable from said face when the mounting means is swung beyond said certain range whereby to permit disengagement of said mounting means from said support by a movement along its pivoting axis.

19. In apparatus of the class described, a cutter bar support, mounting means for a cutter bar having a journal portion received in a bearing formed in said support, the mounting means being swingable relative to said support about the axis of said journal portion, said support having an arcuate ledge thereon concentric with said axis, said ledge having a face in a plane at right angles to said axis, and radially projecting means on said mounting means engaging said face for the support of said mounting means, said projecting means being movable in contact with said face during swinging of said mounting means relative to said support throughout a certain range and being disengageable from said ledge when the mounting means is swung beyond said certain range whereby to permit disengagement of said mounting means from said support by a movement along its pivoting axis.
